CLAIM

The ornamental design for a lighting adjustment device with adjustment knob and faceplate as shown and described.

DESCRIPTION

FIG. 1 is a front, top and right side perspective view of a lighting adjustment device with adjustment knob and faceplate showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines are for the purpose of illustrating environmental subject matter and form no part of the claimed design.

1 Claim, 7 Drawing Sheets
